UNITED STATES PATENT OFFICE.

ROBERT E. CARSWELL, OF MINNEAPOLIS, MINNESOTA, ASSIGNOR TO DISPATCH MOTOR CAR COMPANY, OF MINNEAPOLIS, MINNESOTA, A CORPORATION OF SOUTH DAKOTA.

DESIGN FOR A MOTOR-CASING FOR AUTOMOBILES.

44,234.

Specification for Design. Patented June 24, 1913.

Application filed April 21, 1913. Serial No. 762,737. Term of patent 7 years.

To all whom it may concern:

Be it known that I, ROBERT E. CARSWELL, a citizen of the United States, residing at Minneapolis, in the county of Hennepin and State of Minnesota, have invented a new, original, and ornamental Design for a Motor-Casing for Automobiles, of which the following is a specification, reference being had to the accompanying drawing, forming part thereof.

The single perspective view of the drawing shows a motor casing for automobiles embodying the improved design.

I claim:

The ornamental design for a motor casing for automobiles as shown.

ROBERT E. CARSWELL,

In the presence of—

EDITH E. HANNA,

HARRY D. KILGORE.
